WALL RADIATOR ENCLOSURE

Ellis G. Powell, Michigan City, Ind., assignor to
 C. A. Dunham Company, Marshalltown, Iowa,
 a corporation of Iowa

Application August 7, 1940, Serial No. 351,686

9 Claims. (Cl. 237—79)

This invention is directed to new and useful improvements in wall radiator enclosure of the type that is usually installed in a building during its construction.

This type of enclosure comprises generally a casing surrounding the radiating means open at its bottom and top to permit circulation of air therethrough by convection and a damper means positioned above the radiating means to control the volume of heated air passing through the 10 casing.

In modern building construction steel window frame and sash is commonly used to increase the fireproofing of the building and inasmuch as the radiating means is generally positioned adjacent a window the enclosure must be constructed to fit and be secured to such steel construction.

It is the primary object of this invention to provide such a metal radiator enclosure that is simply designed so as to be readily assembled with and secured to the modern type of metal window sash construction.

A further object is to provide such an enclosure that is easily opened for cleaning purposes without injury to the interior finish of the space in which it is located.

Still another object is to provide a novel locking means for assembling and holding the enclosure in assembled position.

Another object of this invention is to provide such an enclosure that is not secured to or positioned against the radiating means so that the movement of the heat transferring means due to variation in temperature cannot affect the enclosing structure.

Still a further object is to provide an enclosure of the type described having novel reinforcing means, and shaped to facilitate the application of plaster to the adjacent walls, the installation of base boards and the positioning of insulation between the back of the enclosure and the wall of the space in which positioned.

Still another object is to provide a novel enclosure construction in which the back of the structure has supporting means for the front portion of the enclosure whereby the front may be easily and accurately pivoted into closed or assembled position.

Further objects and advantages will be apparent from a study of the following detailed description.

In the drawings:

Fig. 1 is a front view partly in section and partly in elevation of an enclosure constructed in accordance with this invention.

Fig. 2 is a vertical cross sectional view taken along line 2—2 of Fig. 1.

Fig. 3 is a sectional view taken along line 3—3 of Fig. 2.

5 Fig. 4 is an enlarged detail view of the securing means shown in the uppermost part of Fig. 2.

Fig. 5 is a sectional view similar to that of Fig. 2 of a slightly different form of enclosure embodying this invention.

Fig. 6 is a cross-sectional view taken on line 6—6 of Fig. 5.

In detail the enclosure comprises a back plate 1, a front assembly 2 and a damper assembly 3. The upper edge of back plate 1 is bent to horizontal position to form a flange 4 extending from the plate 1 in a direction away from the wall 5 adjacent which the enclosure is to be positioned. This flange 4 is provided with downwardly projecting pins 6 which are adapted to fit into holes 7 that are drilled in the underlip 8 of the window sill 9.

The lower edge of plate 1 is provided with a lip 10 extending horizontally toward the wall 5 to add to the stiffness of the back plate 1. The 25 lower portion of plate 1 is further strengthened horizontally by means of angle member 11 welded to the back plate from side to side. The back plate 1 is reinforced vertically by channel members 12 positioned on the wall side of the plate.

A back sheet support plate 13 is the means of anchoring the lower part of the plate 1. Plate 13 is provided with vertical slots 14 for receiving lock bolts 15 which extend through the lower side of plate 1 are welded thereto and are secured to plate 13 by means of nuts 16. The slots provide adjustment to compensate for the variations resulting from the usual tolerances in measurement. Support plate 13 extends downwardly terminating in a lip 17 provided with holes for 40 wood screws 18 which secure the plate to the wood screw 19.

As best shown in Fig. 3 the vertical edges of plate 1 are formed at right angles to the back and extend away from wall 5 to form lips 20. These lips are each provided with an inwardly extending pin 21 for purposes hereinafter described. Adjacent the bottom of each of the lips 20 are outwardly extending pins 22.

In order to provide horizontal reinforcing for the top portion of plate 1 an angle member 23 extends across the plate and is secured thereto by means of bolts 24 welded to plate 1 and extending through slots 25 in angle 23 and nuts 26. The slots provide for vertical adjustment of angle member 23 which is clamped in position

to form a recess or groove 27 between the lower surface of underlip 8 and the upper surface of angle member 23.

It is clear that the above back construction permits it to be installed as the trim is prepared for plastering. Later the radiating means may be positioned relative thereto and the front of the enclosure assembled on the back as will be hereinafter described. This construction provides a plaster stop so the plaster may be easily brought flush against the sides with the excess flowing around the edges to present a neat finished appearance.

If it is desired to position insulation between the back plate and the wall this may be readily done by positioning the insulating material between the channel members 12. However, without insulating material positioned there the air space between the wall and the back plate will provide a certain insulating effect.

Furthermore a back plate so constructed may be installed as the building is being constructed and will in no way interfere with the subsequent installation of the mop or base board here shown as 28.

The front assembly 2 comprises a front plate 29 the vertical edges of which are formed at right angles relative thereto forming lips 30 which abut the edges of side pieces 31 which are welded thereto, which joint is reinforced by batten strip 32. This combination provides vertical bracing. Horizontal bracing is provided by channel member 33 positioned centrally across front plate 29. The lower edge of frontplate 29 is strengthened horizontally by being folded back on itself as shown at 34.

The upper portion of plate 29 is bent backwardly at about a 30° angle in which portion is formed a slanting punched grille 35. The upper edge is bent to form a rearwardly extending horizontal lip 36.

The bottom edges of side pieces 31 have slots 37 near the rear edges of the pieces and substantially centered in the lower edges of said pieces 31 are arch-shaped openings 38.

A novel, eccentric positioning and locking mechanism is secured to each of the side pieces 31 adjacent the grille 35 and comprises a hook member 39 collared about a cam or disk 40 eccentrically positioned relative to concentric cylindrical projections or pins 41 and 42 and forming a part thereof. The larger projection 41 is provided with an hexagonal recess 43 and is journaled in an opening in side piece 31. The other projection is journaled in an opening in a stirrup piece 44 shown partially broken away which is secured to the side piece 31. A pin 45 projects inwardly from the inner surface of each side piece 31 adjacent the hook member 39 to provide a stop for member 39.

The damper assembly 3 comprises a rectangular valve member 46 of substantially the same length and width as the inside of the enclosure, pivotally positioned across the center of the enclosure by means of shafts 47 and 48 which are flattened at their inner ends and secured to the valve member 46 by means of rivets 49. Surrounding shaft 47 between the valve member and side piece 31 is a compression spring 50 which normally forces the valve towards the opposite end of the enclosure. On the outer end of shaft 47 which extends through side piece 31 is secured a handle 51. Shaft 48 is journaled in a stirrup shaped fastening member 52 which is secured to side piece 31. This fastening mem-

ber is provided with openings 53 adapted to receive the rounded end portion of finger 54 for holding the valve in various positions.

This enclosure is adapted to enclose any type of heat radiating means which, as illustrated, comprises a hot fluid conducting pipe 55 having heat radiating fins 56. The radiating means has inlet and outlet connections 57 and 58 respectively (the illustration is for use with a down-feed steam line) which extend into the enclosure through arch shaped openings 38 without in any way being secured to or resting upon any part of the enclosure assembly.

The above described form of radiator enclosure is assembled as is now described.

As soon as the steel window sash is installed in the building this can be done. The appropriate holes 7 must be drilled in the underlip 8 and then the back plate 1 may be hung thereon with pins 6 positioned in holes 7. The back sheet support plate 13 is then adjusted on bolts 15 and secured at proper position to bring lip 17 flush with upper surface of wood screed 19 to which it is then secured by means of screws 18. Angle 23 is secured to plate 1 by means of bolts 24 after being properly adjusted so as to provide a recess or seat 27 of correct size for receiving lip 36. At this point the plastering may be done and thereafter the radiating means may be installed in proper relation to the back plate.

To complete the enclosure the front assembly 2 is then positioned relative to the back with side pieces 31 outside of lips 20 and slots 37 engaging pins 22. The front assembly is then pivoted on pins 22 toward the wall 5 until lip 36 is positioned in recess 27 and against back 1, as clearly shown in Fig. 4. Thus the pins 22 provide support and guide means.

At this point the locking means is brought into operation. An hexagonal tool is positioned in hexagonal recess 43 and turned. The turning of the eccentric or cam will cause the outer end of the hook member 39 to first be lifted, then be moved toward the wall, then lowered to engage pin 21 and then tend to move away from the wall to draw the front assembly firmly against the back plate. A spring washer 59, or any other suitable means may be used for causing sufficient friction to hold the hook in any desired position. Pin 45 is so positioned to prevent hook member 39 from falling below operating position for pin 21.

The valve 46 of the damper assembly is operated by means of handle 51. In order to position it any desired position the handle is rotated as desired to cause the round ended finger 54 to be disengaged from any of the holes 53 by moving against spring 50. Handle 51 is released at the desired position and the spring 50 will hold it there. The channel member 33 provides a stop for the valve in closed position and a damper stop for open position is provided by angle member 60.

To open the enclosure for cleaning it is only necessary to reverse the operation of the locking mechanism which action will move hook members out of engagement with pins 21 and will permit the front assembly to be pivoted away from back plate 1 and then lifted from pins 22.

Another embodiment of this invention is shown in Figs. 5 and 6, in which the general construction, the damper assembly, the locking means are much the same as above described. Parts which are of the same construction as

hereinbefore described will bear the same reference characters.

The main difference in the construction shown in Figs. 5 and 6 are necessitated by the different form of window sash 9 in which the underlip 61 terminates in a lip 62 upturned at about 45°. In such a case the back plate 63 must be formed with an upper edge bent downwardly at substantially the same angle as the upturned lip 62, to form a downturned lip 64. A reinforcing angle member 65 provided with vertical slots 66 and of the same contour as the upper edge of plate 63 is clamped to plate 63 by means of bolts 67 to firmly clamp the back to the window sash. A right angle reinforcing member 68 likewise provided with vertical slots 69 to permit adjustment, is also secured to back plate 63 by the same bolts 67 with its horizontal portion 70 spaced below the lower surface of the horizontal portion of underlip 61 to provide a recess or groove for horizontal lip 36 of the front assembly.

The lower portion of the back plate 63 is formed to provide a parallel but inwardly spaced fastening edge 71 for securing the plate directly to the wall by means of screws 72. Horizontal reinforcing for the bottom of the back plate is provided by a channel member 73 which also acts as a stop for the construction of the cement or plaster baseboard 73a and vertical reinforcement is provided by channel members 74.

The damper assembly is fundamentally the same as hereinabove discussed the only difference being in the stop means in which a plurality of depressions 75 are used in place of holes 53. It is clear that any stop means may be used such as for example a resiliently held ball carried by the movable valve to cooperate with the depressions.

Likewise the eccentric locking mechanism may be constructed to be operable by any well known means such for example by replacing the hexagonal recess with a slot so that it may be operated by a screw driver.

In order to present a neater appearance it may be desirable to indent a part of the side of the enclosure at the operating end of the damper assembly so that the operating handle may be flush with the side or a knob may be substituted for the handle. All of such details are well known in the art and form no part of this invention.

The advantage of providing a slanting grille 35 is that no object can be placed thereon to interfere with proper heat circulation.

The back construction shown in Fig. 5 is particularly adapted for buildings in which cement or plaster baseboards are to be used for the channel member 73 provides a stop which enables the workman to rapidly and neatly construct such a baseboard.

We claim:

1. In combination with a window sill, a radiator enclosure comprising a front member and back member removably associated, said front member comprising a front plate provided with a grille at its upper portion, a lip at its upper edge for association with the sill in assembled position, and side pieces provided with openings extending to the lower edges for accommodating radiating means, said back member comprising a back plate, a top flange for anchoring to the window sill, horizontal reinforcing means adjacent the top flange forming a seat for the lip of the front member, pins on one of said members, slots on said other member for cooperating with the pins whereby one member pivotally supports

the other, and locking means carried by said members whereby said members are releasably held in assembled relation.

2. A wall radiator enclosure comprising a back plate provided with a lip at its upper edge anchoring the top of said back portion, means securing the lower portion of the back in substantially vertical alignment with the upper portion, a horizontal reinforcing member on the upper part of the back having a horizontal surface, lips extending from the sides of the back and at right angles thereto, a horizontally extending pin on each of said lips adjacent the lower portion thereof, a front assembly comprising a front plate, a slanting grille, side pieces and a horizontally extending top lip, a slot in the lower portion of each side piece engaging the said pins whereby the front assembly is pivoted into assembled position with the back plate, said horizontal lip fitting upon the horizontal surface of the reinforcing member, means positioned on said front assembly and means on said back plate adapted to cooperate to lock said parts in assembled position.

3. In combination with a metal window sash positioned in a room to be heated and provided with an underlip, a radiator enclosure comprising a back plate having a top lip engaging with the underlip of said window sash to support the back plate, means anchoring the lower end of the back plate to an adjacent portion of the room, an angle reinforcing member secured to the back plate adjacent the top and spaced from the underlip of the sash to provide a groove, a front assembly means having a top lip engaging said groove, pivotal means removably joining said back plate and front assembly together, and locking means on said plate and front assembly adapted to cooperate to hold the enclosure in assembled position.

4. In combination with a window sash having an underlip provided with holes, a radiator enclosure comprising a back means and a front means, a lip along the upper edge of said back means, pins in said lip extending downwardly and into the holes in said sash underlip, an angle member secured to said back means and presenting a horizontal surface spaced from said underlip to form a groove, a horizontal lip on the upper part of said front means positioned within said groove and against said back means, means pivotally and removably joining said front means to said back means adjacent the lower parts thereof and locking means carried by one of said means holding the horizontal lip in the groove.

5. In combination with a metal window sill, a radiator enclosure comprising a back member and a front member removably associated therewith, said back member comprising a back plate having a flange along its upper edge overlying a part of the sill, an angle member secured to the back plate and bearing against the undersurface of part of the sill to clamp the back thereto, a second angle member secured to the back plate adjacent the top and forming a horizontal seat, said front member comprising a front plate having a top lip positioned on said seat and means at the bottom of the enclosure pivotally and removably joining the members together.

6. In combination with a metal window sill positioned in a building, a radiator enclosure comprising a back member anchored to the sill adjacent the wall and a removable front member, said back member comprising a back plate provided with a flange at its upper edge anchored to

a portion of the sill, means anchoring the bottom of the plate in substantially vertical position to an adjacent part of the building, lips extending from the sides of the plate to provide plaster stops, a vertically adjustable angle member adjacent the top and providing a horizontal seat, said front member comprising a front plate provided with a lip at its upper edge resting upon said seat, a grille portion near the top, side pieces and means near the bottom of the enclosure pivotally supporting the front member on the back member and locking means carried by said front member holding said parts in assembled position but permitting the removal of said front member from the back member.

7. In combination with a metal window sill in a wall, a radiator enclosure comprising a back member comprising an outwardly extending flange at its upper edge said flange overlying a part of said sill and secured thereto, an inwardly extending flange at its lower edge secured to the wall to space the member therefrom, an outwardly extending seat means adjustably secured to the back at its upper end, a front member comprising a front plate, sides, a grille portion near the top and a lip means at its upper edge resting on said seat means and guide means joining said front and back members together adjacent the bottom of the enclosure.

8. In combination with a metal window sill positioned in a room, a radiator enclosure comprising a back member comprising an outwardly extending flange at its upper edge said flange over-

lying a part of said sill and secured thereto, a vertically adjustable anchoring means secured to the back member at its lower edge and anchoring said back in vertical position to an adjacent part of the room, an outwardly extending seat means adjustably secured to the back at its upper end, a front member comprising a front plate, sides, a grille portion and a lip means at its upper edge resting on said seat and guide means removably joining said members together adjacent the bottom to correctly position them for assembly.

9. In combination with a metal window sill positioned in a wall of a room, a radiator enclosure comprising an anchored back member and a removable front member, said back member comprising a back plate, a flange at the upper edge of said plate anchored to said sill, lips along the sides edges of the plates forming plaster stops, vertical reinforcing channel members spaced on the wall side of the back, means securing the lower end of the plate to an adjacent portion of the room in substantial vertical alignment with the top, a horizontal reinforcing angle member adjacent the top and providing a seat spaced from the sill portion to which the plate is anchored, said front member having a lip at its upper edge, and means on the lower part of the lips of said back member for receiving and supporting the front member with said front member lip positioned on said seat.

ELLIS G. POWELL.
